CHARLES LAMB, OF LOS ANGELES, CALIFORNIA, ASSIGNOR OF ONE-HALF TO M. G. BRUMBLY, OF WALNUT PARK, CALIFORNIA

HIGH PRESSURE PUMP PISTON

Application filed September 26, 1927. Serial No. 222,171.

This invention relates to pump pistons and relates particularly to a piston which is adapted for use in slush pumps or other pumps handling fluids which carry abrasive substances.

In the oil producing industry a slush pump is used to pump rotary fluid to the bit of the apparatus which is drilling the well. This rotary fluid must be under a high pressure to insure circulation, and it carries much abrasive since it is in the form of a thin mud. For these two reasons the wear on the pistons in the slush pumps is considerable, and consequently if the pump is in operation for but 15 a short time the piston becomes worn so that it is very inefficient. In order that the pump operate efficiently, it is necessary at frequent intervals to mechanically adjust the piston into proper working contact with the cylinder 20 der of the pump.

One of the objects of my invention is to provide a pump piston which is self-adjusting and which will automatically be maintained in proper contact with the cylinder of 25 the pump. I have found that the initial wear on the pump piston is at the ends thereof and works toward the center. I have also found that if the ends of the piston are always in proper contact with the cylinder that 30 the central part will not be subjected to wear. In accordance with these findings I have constructed a pump piston formed of a resilient material, such as rubber having a central part which is adapted to be forced into 35 peripheral engagement with the cylinder by a mechanical adjustment and having end portions which are retained in proper working contact with the cylinder by hydraulic pressure in the cylinder ends.

40 It is accordingly one of the objects of this invention to provide a piston in which the central portion is mechanically held in engagement with the cylinder and the end portions are hydraulically held in engagement 45 with the cylinder.

If the rotary fluid or slush which is handled by the pump is allowed to come into direct contact with the ends of the rubber piston, the ends thereof will be rapidly worn

away and the life of the piston will be very short.

It is an object of this invention to provide a pump piston in which the rubber body will be protected from direct contact with the 55 fluid being handled by the pump and consequently will be protected from considerable of the abrasive action of the fluid.

Other objects and advantages will be pointed out in the following description in which reference will be had to the accompanying drawings.

In the accompanying drawings in which a preferred form of my invention is illustrated:

Fig. 1 is a utility view.

Fig. 2 is a cross section of the piston of my invention before it is inserted into the pump cylinder.

Fig. 3 is a cross section similar to Fig. 2 70 showing the pump piston inserted into a pump cylinder.

Fig. 4 is a section taken on the line 4—4 of Fig. 3.

Referring in detail to the drawings and 75 particularly to Fig. 1, the slush pump has a driven end 11 in which the rotary fluid or slush is handled and a drive end 12. The driven or slush end of the pump has a cylinder 13 in which the piston 14 embodying the 80 features of my invention is adapted to be reciprocated. The piston 14 is attached to a piston rod 16 which extends outward from the cylinder 13 through a suitable gland 17. This rod 16 extends to the drive end of the 85 slush pump where it is caused to reciprocate.

Referring to Figs. 2 to 4, the details of the invention will be described. The piston 14 of the invention provides a resilient piston body 20. This body 20 is preferably made of a rubber or rubber composition having good wearing qualities. Formed through the center of this resilient piston body 20 is a tapered opening 21 through which a tapered portion 22 of the rod 16 extends. The resilient piston body 20 is provided with an annular reinforcement 23 which surrounds the opening 21. This reinforcement 23 is semi-rigid and is formed of a ma-

terial which is harder and tougher than the material forming the other part of the resilient piston body. In actual practice I form this reinforcement of a rubber composition known as "Whalite". It should be understood that any other suitable material may be substituted.

The central portion 25 of the resilient piston body 20 is cylindrical and is of such a 10 diameter that this portion may be moved into the cylinder 13 without requiring it to be constricted or with but a minimum of constriction. The end portions of the resilient piston body 20 are provided in the form of end lips 26. These end lips 26 are conical and are 15 largest in diameter at their outer ends. These end lips 26 are formed so that they are normally of a larger diameter than the diameter of the cylinder 13, so that when the piston 20 is inserted in the cylinder 13 the end lips must be forced inward or constricted. Formed at the ends of the resilient piston body 20 directly inside the end lips 26 are 20 annular fluid channels 27.

Placed on the tapered portion 22 of the rod 16 is a pair of plates 29. One plate 29 is adapted to engage a shoulder 30 of the rod 16, and the other plate 29 is provided with a hub 31 which is engaged by a nut 32 adapted 25 to be screwed onto a threaded portion 33 of the rod. The plates 29 have inner faces 35 which are adapted to contact end faces 36 of the resilient piston body 20. The end plates 29 are but slightly smaller in diameter than 30 the cylinder 13. It is preferable to have the end plates 29 about one-sixteenth to one-eighth of an inch smaller in diameter than the cylinder 13. The end plates cover the annular channels 27 and are provided with 35 openings 39 which connect to the annular channels 27 so that fluid may pass thereinto. Projecting inward from the inner faces 35 of the end plates 29 are compressing means in the 40 form of compressing rings 40. These compressing rings 40 extend into annular cavities 41 which are formed in the opposite ends of the resilient piston body 20 around the reinforcement 23. The inner faces 42 of the compressing rings 40 are made conical, as 45 illustrated, for the purpose of pressing the hub ends 44 of the resilient piston body 20 (which are provided by forming the body 20 with the annular cavities 41) inward into fluid-tight contact with the tapered portion 50 22 of the rod 16.

In Fig. 2 the piston 14 is shown assembled on the rod 16 before it is inserted in the cylinder 13. The left end of the body resilient material 20 must be mechanically constricted so that it will enter the cylinder 13. When this is done, the piston is moved into the cylinder 13 so that only the nut 32 is accessible. The nut 32 is then screwed onto the threaded portion 33, and the parts are moved into the position shown in Fig. 3. In the

first place, it will be seen that the end lips 26 pressurally engage the cylinder 13, due to the fact that they are constricted when the piston 14 is inserted. When the nut is screwed up and the plates are forced together, the entire resilient piston body 20 is placed under compression. The result is that the end faces 36 of the resilient piston body are moved together so that the inner portion of the resilient piston body is moved inward into fluid-tight contact with the tapered portion 22 of the rod 16, and the central portion 25 of the resilient piston body 20 is forced outward into pressural contact with the cylinder 13. The compressing rings 40 assist in compressing the resilient piston body, for the most part forcing the hub ends 44 inward into fluid-tight contact with the tapered portion 22 of the rod 16.

When the pump is set into operation, the pump piston 14 is reciprocated and a fluid pressure is alternately built up in opposite ends of the cylinder 13. When the piston is moving to the left, the fluid pressure is on the left side thereof. The fluid under pressure will pass through the openings 39 in the left end plate 29 and into the left annular channel 27. This fluid under pressure forces outward on the left end lip 26 and maintains it in fluid-tight contact with the cylinder 13. When the piston 14 is initially installed, the pressure of the end lips, due to their being constricted, is sufficient to maintain a fluid-tight engagement, but when the end lips become worn this engagement is not so strong due to the constriction of the end lips, but the fluid pressure makes up for this and preserves a fluid-tight engagement. By always maintaining the end lips in fluid-tight contact, practically no abrasive will get to the central portion 25 and wear it away. For this reason the wear at the central portion 25 will not be very great and mechanical adjustment will not be required.

By extending the end plates 29 outward so as to cover the ends of the resilient piston body 20, they are protected from the abrasive fluid carried by the slush pump and will not be worn away as they would were these ends exposed. In practice I find that the best protection is procured when the end plates are but slightly smaller in diameter than the cylinder 13. This is particularly true where a very high pressure of the fluid must be obtained. Of course, where the pressure is lower the wear on the resilient piston body 20 is not so great and it will not be necessary to extend the end plates 29 out so far. Since the annular channels 27 are covered by the end plates 29, the openings 39 are provided.

In the drawings I have shown a preferred form of the invention for high pressure pumps. In pumps of lower pressure the design shown is not necessary and a cheaper construction may be provided. For example,

the end plates 29 may be made much smaller in diameter than the cylinder 13, and the compressing rings 40 may be eliminated. Where the pressure is very high it is quite 5 essential that a fluid-tight engagement be maintained between the resilient piston body 20 and the tapered portion 22 of the rod 16 so that no fluid will leak therethrough, since if any fluid leaks therethrough a passage is 10 soon worn through the resilient piston body and it is ruined.

In the construction herein disclosed, the entire body of the piston comprises a composite resilient body which is applied directly 15 to the piston rod or shaft between two end plates, one of which is stationary and the other of which is axially adjusted upon the rod to compensate for wear of the piston. Such take-up for wear may be effected from 20 time to time without removing the piston from the cylinder, by merely tightening up of said nut 32, this progressive tightening up of said nut being possible since the adjustable end plate 29 does not at any time engage any 25 abutment shoulder.

The tougher core portion 23 of the composite piston body is of particular advantage in that it produces a more firm grip of the piston body upon the piston rod than if the 30 entire body were made of softer rubber, and it also provides the piston rod bore 21 with a more substantial wall surface which is less liable to injury due to careless or hurried installation.

35 The annular grooves on each side of the piston body 20 may be defined as an outer primary channel 27 and an inner secondary channel 41, the primary channel 27 defining an outer peripheral lip 26, the secondary 40 channel 41 defining a hub end 44, and both channels defining an inner or secondary lip 45. With a piston body of this character the relative compressing movement of the end plates causes the rings 40 to exert an inward 45 radial compressing force upon the hub ends 44 so that said hub ends firmly grip the piston rod and provide an effective seal against leakage of fluid through the bore of the piston. The secondary lip 45 is of particular 50 value since under the influence of the pressure in the primary or pressure channel 27 said lip 45 grips the ring 40 and forms a seal against leakage of the fluid inwardly along the end plates.

55 I claim as my invention:

1. In combination: a piston rod; a piston consisting of a composite resilient piston body mounted directly on said rod, said body having a relatively harder and tougher annular core surrounding said rod, said core being diametrically enlarged intermediate its ends; end plates engaging opposite ends of said piston body; and means for causing relative movement of said plates towards each 60 other to axially compress and radially ex-

70 pand said resilient body to working contact with the wall of a cylinder in which it is adapted to operate, and to further axially compress and radially expand said resilient body to compensate for wear.

2. In combination: a piston rod; a piston 75 consisting of a resilient piston body mounted directly on said rod, the opposite end walls of said body having formed therein an outer concentric channel defining an outer peripheral lip and an inner concentric channel defining an end hub; end plates engaging opposite ends of said piston body, each plate having a concentric flange extending inwardly 80 into the companion inner channel of said body to confine the adjacent end hub thereof and each plate being of sufficient diameter to cover the respective outer channel of said body and thereby form an annular pressure chamber, there being in each plate passages 85 communicating with the respective pressure chamber and the exterior of said piston; and means for causing relative movement of said end plates towards each other whereby the resilient piston body will be axially compressed and radially expanded to working 90 contact with the wall of a cylinder in which it is adapted to operate, and to further axially compress and radially expand said resilient body to compensate for wear, said compression causing the plate flanges to clamp the end hubs of said body upon the piston rod.

3. In combination: a piston rod; a piston 95 consisting of a composite resilient piston body having a relatively harder and tougher 100 annular core mounted directly on said rod, the opposite end walls of said body each having formed therein an outer concentric channel defining an outer peripheral lip and an inner concentric channel defining an end 105 hub; a relatively stationary end plate engaging one end of said piston body; a relatively movable end plate engaging the opposite end of said piston body, each end plate having a concentric flange extending inwardly into the 110 companion inner channel of said body to confine the adjacent end hub thereof and each plate being of sufficient diameter to cover the respective outer channel of said body and thereby form an annular pressure chamber, there being in each plate passages 115 communicating with the respective pressure chamber and the exterior of said piston; and means cooperating with said piston rod to urge the movable end plate towards the stationary end plate whereby the resilient piston body will be axially compressed and radially expanded to working contact with the wall of a cylinder in which it is adapted to operate, and to further axially compress and radially expand 120 said resilient body to compensate for wear, said compression causing the plate flanges to clamp the end hubs of said body upon the piston rod.

4. In combination: a piston rod; a piston 125

consisting of a composite resilient piston body having a relatively harder and tougher core mounted directly on said rod, the opposite end walls of said body having formed therein an outer concentric channel defining an outer peripheral lip and an inner concentric channel defining an end hub; end plates engaging opposite ends of said piston body, each plate having a concentric flange extending inwardly into the companion inner channel of said body to confine the adjacent end hub thereof and each plate being of sufficient diameter to cover the respective outer channel of said body and thereby form an annular pressure chamber, there being in each plate passages communicating with the respective pressure chamber and the exterior of said piston; and means for causing relative movement of said end plates towards each other whereby the resilient piston body will be axially compressed and radially expanded to working contact with the wall of a cylinder in which it is adapted to operate, and to further axially compress and radially expand said resilient body to compensate for wear, said compression causing the plate flanges to clamp the end hubs of said body upon the piston rod.

5. A piston body comprising a cylindrical body of resilient material having an axial bore adapted to receive a piston rod, the end walls of said body each being formed to provide an outer concentric primary channel defining an outer peripheral lip and an inner concentric secondary channel defining an end hub, both channels defining an intermediate concentric secondary lip.

6. A piston body comprising a cylindrical composite tubular body of resilient material having a relatively harder and tougher core surrounding the bore thereof, the end walls of said body each being formed to provide an outer concentric primary channel defining an outer peripheral lip and an inner concentric secondary channel defining an end hub, both channels defining an intermediate concentric secondary lip.

7. A cylindrical tubular composite resilient piston body having axially disposed hubs at its opposite ends and provided with a relatively harder and tougher annular core surrounding its bore throughout the length of said body and its end hubs.

8. A cylindrical tubular composite resilient piston body having an outer annular portion of relatively resilient material and an inner core of harder material, there being a shaft opening through said core, said core being enlarged intermediate its ends so that it will grip a shaft on which it is placed when axial pressure is placed on said core.

In testimony whereof, I have hereunto set my hand at Los Angeles, California, this 17th day of September, 1927.

CHARLES LAMB.
